SOUND DEADENING DEVICE FOR MUSICAL INSTRUMENTS

William E. Strobach, Des Moines, Iowa

Application July 25, 1951, Serial No. 238,484

4 Claims. (Cl. 84—453)

1

My invention relates to reducing and deadening the sound produced on musical instruments.

The principal object I have in mind is to provide a means whereby a person can practice on a musical instrument without having the sound therefrom interfere with persons in relatively close proximity such as adjoining rooms, apartments, buildings or the like.

To acquire and maintain any degree of proficiency in the use of a musical instrument requires continuous practicing. These periods of practice necessitate hard work and concentration and many hours must be devoted to the repeated playing of scales, sustained tones and the like. It is to be understood that all practicing is not confined to playing pleasant harmonies and obviously the continued repetition of tones and sounds produced in practice can and do become monotonous not only to the person producing them but even more so to others who may be within hearing range. Certain instruments create sounds that carry a long distance and one practicing on the instruments, such as a trumpet or saxophone, can cause annoyance to an entire neighborhood.

Knowledge of the fact that the noise of one's instrument is disturbing to others and may even be considered objectionable by some is a psychological drawback to the musician who finds it necessary to spend many hours each day perfecting and maintaining his skill. The inhibition of practice noise is a real problem and especially so for the individual who has no desire to overstrain the patience and tolerance of his neighbors. He can, of course seek out a sound proof room or perhaps mute his tones in a clothes filled closet but the former is not generally available and the latter is far from convenient.

Therefore, the object of my invention, as I have stated above, is to make it possible for a musician to practice his instrument free from the inhibition that the sounds he produces will be annoying to others. I propose to accomplish this objective by providing an enclosure for the instrument that includes sound deadening properties in its construction.

Another object of my invention is to provide a sound deadening enclosure for a musical instrument that will not interfere with the user hearing the notes he produces but will limit the carrying effect of the tones so that they will be substantially confined within a relatively small area in the immediate vicinity of where they are produced.

A still further object of this invention is to produce a device of the above class that will not interfere with the fingering of the keys or valves of the instrument so enclosed.

A still further object of my invention is to provide a sound deadening device having the above characteristics that may be easily moved or carried.

Still other objects of this invention are to provide a sound deadener of the above classes that can be adapted to different type instruments and

2

that are equally serviceable for the novice or the professional musician.

These and other objects will be apparent to those skilled in the art.

5 My invention consists in the construction, arrangement, and combination of the various parts of the device, whereby the objects contemplated are attained as hereinafter more fully set forth, pointed out in my claims, and illustrated in the accompanying drawings, in which:

Fig. 1 is a perspective view of my sound deadening case adapted for use with such straight reed wind instruments as a clarinet, soprano saxophone and the like,

10 Fig. 2 is an enlarged longitudinal section view taken on the line 2—2 of Fig. 1, with the broken lines indicating an instrument placed therein.

15 Fig. 3 is an enlarged longitudinal sectional view of this sound deadener taken on the line 3—3 of Fig. 2, and

20 Fig. 4 is an illustration of this device adapted for use with a saxophone.

25 Referring to the drawings and particularly Figs. 1—3, I have preferably selected a straight wind instrument 10 by which to illustrate my invention. It is to be understood, however, that the principle of my invention is not limited in use to the particular instrument shown. My invention lies in boxing in the sound from the instrument and for this purpose I provide an enclosed case or housing 11 that has a removable lid or cover 12. In the construction of the case 11, including the cover 12, the inside is lined with any suitable 30 material 13 having sound deadening properties and in arranging such material 13 I leave a dead air space 14 between the material 13 and the inner walls of the case 11 as shown in Figs. 2 and 3. The overall shape of the case 11 will vary depending upon the instrument it is designed to be used on. In Figs. 1—3 an elongated rectangular case is shown that is narrower at one end than at the other and is particularly adapted for straight wind reed instruments such as clarinets and soprano saxophones. These instruments will 35 emit sounds at different places throughout their length depending upon the opening and closing of different pads and consequently to deaden the sounds therefrom as contemplated by my invention it is necessary to have all portions of the instruments where sound may emerge, contained within the case 11. This is done by removing the cover 12 and placing the instrument 10 therein as shown in Fig. 2. For this purpose an opening 40

45 is provided in the narrow end of the case 11 so that the neck of the instrument 10 can be projected therethrough sufficiently to support the mouthpiece 16 as illustrated. It is assumed, of course, that the mouthpiece will be mounted after the instrument is encased to avoid any damage to the reed. The opening 15 is sufficiently larger than the neck of the instrument to be encased to eliminate any binding effect thereon and for the purpose of closing the gap at this point after the instrument is encased a washer-like resilient

50

insert 17 is mounted within the opening 15 as shown in Fig. 1. This insert 17 may be of any suitable material such as sponge rubber or the like and will provide a snug but yielding enclosure about the neck to mute the sound at this point. A pair of stop rest members 18 are detachably secured to the inside of the wider end of the case 11 to serve as rests for the bell portion 19 of the instrument. These stops 18 are shown mounted by bolts and wing nuts 20 and may be adjusted as to their spaced relationship to accommodate bell portions 19 of different sizes.

On the respective sides of the casing 11 suitable hand openings 21 and 22 are provided. It is observed that the opening 21 is closer to the opening 15 than the opening 22 to correspond to the relative position of the left and right hand of the person playing the instrument. The openings 21 and 22 are large enough to allow easy insertion of the hands. Each of the hand openings is provided respectively with the resilient washer-like inserts 23 and 24 of the type described above. A plurality of slits 25 radially extending from the openings in the inserts 23 and 24 is preferably provided to eliminate any binding or restriction on the wrists of the hands.

Once enclosed, an instrument as shown in Fig. 2, is played in its usual manner. Preferably the casing is made from suitable lightweight material so as not to become burdensome but it is noted that it may be desirable to use a supporting stand or the like to avoid any unnecessary fatigue from the extra weight of this silencing device. When using this invention the tone will be audible to the maker, though muffled, and can be confined generally to the room where the practicing is being done. The hand holes should be large enough to allow quick and easy withdrawal and insertion of the hand as when turning a page of music.

In Fig. 4 I show my invention constructed to fit the shape of a saxophone and except for its adaptation to the contours of a different instrument its construction is the same as described above.

It will be understood, as previously pointed out, that my invention embodies the idea of encasing those portions of a musical instrument from which sound will emerge. In the case of a soprano saxophone, clarinet, alto saxophone and the like this will necessitate an enclosure for substantially the entire instrument. However, in the case of a trumpet, trombone or the like, where sound emerges only from the bell portion, my invention can be applied by a relatively smaller case enclosing only the bell portion of such instruments.

It will be apparent that while my invention can be adapted to most any type musical instrument, it will find its most practical application when used with smaller instruments and preferably those of the wind variety.

Some changes may be made in the construction and arrangement of my sound deadening device for musical instruments without departing from the real spirit and purpose of my invention, and it is my intention to cover by my claims, any modified forms of structure or use of mechanical equivalents which may be reasonably included within their scope.

I claim:

1. A sound deadening device for a musical wind instrument comprising, a case member, sound deadening properties provided in said case member, said case member adapted to enclose a musical wind instrument to mute and muffle the sounds

produced thereon, two openings in said case member adapted to provide a means for insertion of the hands of a person playing the enclosed instruments, said openings spaced so that when a person's hands are inserted therein they will be in a normal position for playing the enclosed instrument, and a third opening in said case member to provide a means for the protrusion of the mouthpiece of a musical wind instrument encased therein.

2. A sound deadening device for a musical wind instrument comprising, a case member, sound deadening properties provided in said case member, said case member adapted to enclose a musical wind instrument to mute and muffle the sounds produced thereon, two openings in said case member adapted to provide a means for insertion of the hands of a person playing the enclosed instruments, said openings spaced so that when a person's hands are inserted therein they will be in a normal position for playing the enclosed instrument, a third opening in said case member to provide a means for the protrusion of the mouthpiece of a musical wind instrument encased therein, a flexible washer-like insert secured within each of said first two mentioned openings to provide a snug but yielding enclosure about the wrists of a person whose hands are inserted in said openings, and a flexible washer-like insert secured within said third opening to provide a snug but yielding enclosure about that portion of an instrument protruding therefrom.

3. In a device for muting and muffling the sounds produced on a musical wind instrument, a case member, sound deadening properties provided in said case member, means for opening and closing said case member, a plurality of openings in said case member, a washer-like flexible insert arranged within each of said openings, said device constructed and arranged so that a musical wind instrument can be encased therein whereby the mouthpiece of such instrument will protrude from one of said openings and the other openings provide a means by which the hands of a person can be inserted into the case members for the purpose of manipulating the encased instrument.

4. In a device for muting and muffling the sounds produced on a musical wind instrument, a case member, sound deadening properties provided in said case member, means for opening and closing said case member, a plurality of openings in said case member, a washer-like flexible insert arranged within each of said openings, said device constructed and arranged so that a musical wind instrument can be encased therein whereby the mouthpiece of such instrument will protrude from one of said openings and the other openings provide a means by which the hands of a person can be inserted into the case member for the purpose of manipulating the encased instrument, said openings through which the hands of a person are inserted being spaced so that the hands when inserted therethrough are in a normal position for playing the instrument encased.

WILLIAM E. STROBACH.
